UNITED STATES PATENT OFFICE.

JACOB JOHNSON, OF ASHLAND, NEBRASKA.

CHECK-REIN SWIVEL.

SPECIFICATION forming part of Letters Patent No. 320,139, dated June 16, 1885.

Application filed November 11, 1884. (No model.)

To all whom it may concern:

Be it known that I, JACOB JOHNSON, of 5
Ashland, in the county of Saunders and State
of Nebraska, have invented a new and Im-
proved Driving-Line and Check-Rein Swivel,
of which the following is a full, clear, and
exact description.

My invention relates to certain improve-
ments in the swivel-connections for driving-
reins, as will be hereinafter fully described
and claimed.

Reference is to be had to the accompanying
drawings, forming part of this specification,
in which similar letters of reference indicate
corresponding parts in both the figures.

Figure 1 is a plan view of my improved
driving-line and check-rein swivel. Fig. 2 is
a longitudinal sectional elevation of the same.

A forked or **U**-shaped metal piece, A, has
20 the ends of its prongs united by a cross-piece,
B, on which a sleeve, C, is mounted loosely,
around which a strap, D, is passed, connect-
ed with the bit. A pin, E, having a head, F,

is passed through the piece A in such a man-
ner that the head will be on the inner surface 25
of the piece. The pin E is then flattened for
insertion in one end of the check-rein G, and
is held therein by means of rivets.

I am aware that swivel-connections for pre-
venting reins from twisting are not new, and 30
I do not claim such, broadly, as of my inven-
tion.

Having thus described my invention, I claim
as new and desire to secure by Letters Patent—

The combination, with the rein G, of the 35
pin E, formed with a flat portion and a head,
F, and secured to the rein, the yoke A, held
to turn on the pin E adjacent to the head F,
and provided with a cross-piece, B, having a
loose sleeve, C, mounted thereon, and a bit- 40
strap, D, passing around said sleeve, substan-
tially as set forth.

JACOB JOHNSON.
